MOP

Joseph D. Bates, West Springfield, Mass.

Application May 17, 1937, Serial No. 143,176

6 Claims. (CL. 15—119)

This invention relates to mops and, more particularly, has to do with mops having means associated therewith for squeezing water or other liquid out of the mop material.

It has heretofore been proposed to provide a mop comprising a mopping member having associated therewith two wings or squeezing plates which are adapted to be brought into engagement with opposite sides of the mop member in order to squeeze the same therebetween, a device of this type being disclosed and claimed in my prior Patent No. 2,014,488. Such a mopping device has many advantages in ease of operation and squeezing, and in the present invention it is proposed to retain those advantages, although including them in a structure having a simpler and more economic form of construction and embodying a somewhat different method of squeezing.

It is an object of this invention to provide a mopping device which will have associated therewith a plate which may be moved either into or out of engagement with the mop element and which, when moved into engagement therewith, may be further operated to move the mop element into engagement with a fixed face or abutment, whereby the mop element may be squeezed between the movable plate and such abutment.

In accordance with one form which my invention may take, the mop element may be moved against a fixed part of the mop supporting structure, this being a particularly simple and economical form of construction. In another form which the invention may take the mop element may be moved against a fixed plate which is attached to the mop structure. If desired, this fixed plate may be employed also as a means for supporting a squeegee or other wiping device.

Other objects of the invention and features of novelty thereof will be apparent from the following description of the invention and from the annexed drawing, it being particularly understood, however, that the invention is not limited in any way by such description and drawing, or otherwise than by the appended claims.

Referring to the drawing, in which similar reference numerals refer to like parts:

Fig. 1 is a perspective view of a mop device formed according to the present invention;

Fig. 2 is a perspective view of a part of the mop disclosed in Fig. 1 and showing, in particular, the means for hinging and latching the squeezing wing thereof;

Fig. 3 is a sectional view taken on the line 3—3 of Fig. 1;

Fig. 3a is a view similar to Fig. 3, but shows the parts in wringing position;

Fig. 4 is a perspective view of a second form 5 which the invention may take, and

Fig. 5 is a sectional view taken on the line 5—5 of Fig. 4.

According to this invention, I propose to provide a mop device which preferably comprises an elongated mopping element and means associated therewith for squeezing the mop element in order to remove water or other liquid therefrom after use of the device. One form which the invention may take is illustrated in Figs. 1, 2, 10 15 3 and 3a of the annexed drawing and, referring to such figures, it will be seen that the device comprises a mopping element 1, which is preferably formed of sponge rubber or similar material, and which is considerably elongated and 20

is preferably rectangular in cross-section. This mopping element is provided with an elongated supporting or backing frame 2 which is preferably U-shaped in cross-section. One of the longitudinal edges of the mop element is inserted 25 within the U-shaped backing member 2 and is held therein by forcing the sides or free ends of the U-shaped backing member into engagement with the mop member. If desired, one of the

sides of the backing member may be cut off between the bottom thereof and the free edge of such side, and an elongated plate 3 may be attached to the face of such shortened leg of the U-shaped member, as clearly illustrated in Figs. 1 30 and 2. If such a construction is employed, the 35 adjacent free edges of the plate 3 and of the remaining side of the U-shaped member may be forced inwardly against the sides of the mop element 1 and may be turned inwardly toward each

other, as at 4, in order to firmly hold the mop 40 element within the channel shaped backing member. A ferrule 5 may be attached to the channel-shaped backing member 2 in any desired manner in order to provide means for attaching a handle to the mop device for operation thereof.

Means are provided by the invention for squeezing the mop element in order to remove water or other liquid therefrom, and in the form of the invention illustrated in Figs. 1 to 3a the 50 mop element is adapted to be squeezed between a movable plate and one of the fixed sides of the backing member 2. Such a construction preferably embodies a plate which may be normally disposed in an inoperative position away from 55

the mop element and which may, when desired, be moved into engagement with the mop element in order to squeeze the mop element between the plate and the fixed side wall of the backing member. Such a plate is illustrated at 6 in Figs. 1 to 3a, and comprises an elongated member which is preferably slightly curved in cross-section and which is provided with an up-standing handle member 7 which may be grasped in order to operate the plate to its various positions.

Means are provided for pivotally mounting the squeezing plate 6 adjacent the mopping element, and such means are provided by first cutting, in the channel-shaped backing element, spaced apertures 8 which extend entirely through the backing member as clearly illustrated in Fig. 1. The apertures formed in plate member 3 are so formed as to leave bridges 9 extending across the apertures and preferably adjacent the free longitudinal edge thereof. These bridges provide means upon which the plate 6 may be pivotally mounted. Extending from the plate 6, and being spaced along the longitudinal length thereof a distance equal to the spacing of the apertures 8, are two curved arms 10 the free ends of which are coiled about the bridge members which span the apertures 8. The arms 10 are so disposed that they may move within and through the apertures 8 in the backing member 2 when the squeezing plate is moved from operative to inoperative position. It will be seen that when the squeezing plate is in the position illustrated in Fig. 1 it will be in an inoperative position to the rear of and out of engagement with the mop element, whereby the mop may be employed for cleaning purposes without interference from the squeezing plate. If it is desired to squeeze water or other fluid out of the mop element, the plate may be moved, by grasping the handle 7, about the pivotal connection between the arms 10 and the bridge portions 9 in such a manner as to rotate the plate about such pivotal connections and into engagement with the side of the mop element. Further movement of the plate 6 will force the mop element 1 around the backing member and into engagement with the fixed side thereof. It will be seen that by the exertion of sufficient pressure on the plate 6, the mop element may be squeezed between the plate and the side of the backing member.

Means are provided by the invention for releasably retaining the plate 6 in inoperative position to the rear of the backing member 2. Such means comprise one or more extensions 11 which are formed on the rear edge of the squeezing plate 6 and which, when the squeezing plate is in its inoperative position to the rear of the backing member, resiliently engage the side of the backing member in order to releasably hold the plate in inoperative position. It will be apparent that the resilient engagement between the extensions 11 and the backing member will be sufficient only to hold the plate in inoperative position and that the plate may be easily removed from such position.

In a second form which the invention may take, the mop member is adapted to be moved into squeezing engagement with a fixed abutment or plate which is carried by the backing member. Such a form of the invention is illustrated in Figs. 4 and 5 of the drawing and, referring to these figures, it will be seen that the device disclosed in this modification comprises the elongated mop element 20 which is preferably formed of sponge rubber or similar material and which is

preferably rectangular in cross-section. The upper longitudinal edge of the mop element is releasably held between two elongated plate members denoted generally at 21, 22, each of which is angularly bent about an axis extending longitudinally of its length in order to provide two laterally-spaced, parallel, elongated portions. Two of these elongated, parallel portions, which are denoted as 21a and 22a, are adapted to engage the upper longitudinal edge of the mop member therebetween, and screw-threaded bolts 23 are extended through aligned apertures in these portions of the plate members and are provided with wing nuts 24 whereby the plate members 21a and 22a may be tightened against the sides of the mop member to hold the same firmly therebetween. The other portions 21b and 22b of the elongated plate members 21 and 22 are bent from the portions 21a and 22a about an axis extending longitudinally of the plate member, and the portions 21b and 22b are spaced apart in order to receive therebetween one or more squeegee members 25 which may be formed of rubber or other suitable material. The plate members 21b and 22b may be attached together by rivets or other desirable attaching means 26. The plate members 21b and 22b are preferably so arranged with respect to the mop element that when the mop element is in operative position on a floor or other surface, the plate members 21b and 22b and the squeegee associated therewith will extend upwardly and forwardly from the mop device, as clearly illustrated in Fig. 5.

Means are provided by this invention for forcing the mop member 20 into engagement with the rigid assembly formed by the plate members 21b and 22b and the squeegee members included therebetween. Such means comprise the pivotal assembly or frame denoted generally at 30 and comprising the two spaced curved arms 31 and 32 which are respectively pivotally connected to lugs 33, 34 which are formed on opposite ends of the plate member 21a. The arms 31 and 32 may be connected by a longitudinally extending member 35 which is so formed as to provide a handle 36 at its center portion by means of which the pivotal assembly may be operated. Rotatably journaled between the two arms 31 and 32, and preferably extending the entire length therebetween, is a roller 37 which is provided for a purpose to be explained hereinafter. If desired, detent means such as 38 may be provided for releasably holding the pivoted assembly in inoperative position out of engagement with the mop element 20 and to the rear thereof. A ferrule 39 may be attached by any suitable means to the plate member 21b in order to provide means for attaching a handle member to the mop device.

In the operation of the device described, it will be seen that the mop may be employed for cleaning purposes and that, during such operation, the pivoted assembly 30 will be disposed in inoperative position to the rear of the mop element, as clearly illustrated in Fig. 4, and will be releasably held there by means of the detent means 38. When it is desired to squeeze water out of the mop element, the pivoted assembly 30 may be rotated about the pivotal connection thereof with the lugs 33, 34 into such a position that the roller 37 engages one side face of the mop element. Continued movement of the pivoted assembly, which may be effected by means of the handle 36, will cause the mop element 20 to be bent about the line of the attachment to the plates 21a, 22a and to be forced by the roller 37 into engagement

with the lower side of the rigid assembly formed by the plates 21b, 22b and the squeegee means arranged therebetween. It will be apparent that if sufficient pressure is applied to the pivoted assembly the mop member 20 will be squeezed between the roller 37 and the fixed assembly to thereby remove all water or other liquid from the mop element.

If desired, the squeegee 25 may be used as a wiping element by merely turning over or reversing the entire device to cause the squeegee to be placed in operative relation to the surface which is to be cleaned. In this use of the device the pivoted assembly 30 will of course be held in an operative position by means of the detent 38.

While I have illustrated and described certain forms which my invention may take, it will be apparent to those skilled in the art that other modifications of the invention may be made and that improvements may be made therein without departing in any way from the spirit or scope of the invention, for the limits of which reference must be had to the appended claims.

What is claimed is:

1. A mop device comprising a backing and supporting member having elongated parallel spaced side walls defining an elongated opening therebetween, an elongated cleaning member formed of sponge material and having one longitudinal edge portion thereof positioned within the elongated opening in said backing and supporting member and the remainder thereof extending outwardly from the backing and supporting member to provide a mop portion, an elongated squeezing member arranged adjacent and in parallelism to said backing and supporting member and being pivotally connected thereto adjacent one of said side walls thereof, the pivotal connection of said squeezing member to said backing and supporting member being so constructed and arranged that the squeezing member may be moved from a position at the rear of the backing and supporting member in which it is removed from contact with said mop portion to a position in which it engages one side wall of the mop portion throughout substantially the entire length thereof and causes the mop portion to be folded about the longitudinal edge of one of the side walls of

the backing and supporting member with the opposite side wall of the mop portion in engagement with the side wall of the backing and supporting member which is opposite to the side wall adjacent which the squeezing plate is pivotally connected, whereby the mop portion is squeezed between the squeezing member and said side wall, and means for normally maintaining the squeezing member out of engagement with said mop portion.

2. A mop device according to claim 1, in which the squeezing member comprises an elongated plate which is arcuate in cross-section, and which is pivotally connected to said backing and supporting member by curved arms extending from one edge of said plate and having their free ends pivotally connected to one side wall of said backing and supporting member.

3. A mop device according to claim 1, in which the squeezing member comprises a pair of spaced arms which are respectively pivotally connected adjacent the opposite ends of said backing and supporting member for movement toward and away from said mop portion, and an elongated member having its opposite ends connected to said arms.

4. A mop device according to claim 1, in which the squeezing member comprises a pair of spaced arms which are respectively pivotally connected adjacent the opposite ends of said backing and supporting member for movement toward and away from said mop portion, a handle member connecting said spaced arms and forming therewith an open frame, and an elongated mop-engaging member having its opposite ends connected to said arms.

5. A mop device according to claim 1, in which at least one of said side walls has an elongated portion extending away from the mop portion and forming an obtuse angle with the portion thereof which engages the cleaning member.

6. A mop device according to claim 1, in which each of said side walls has a portion extending away from the mop portion and forming an obtuse angle with the portion thereof which engages the cleaning member, said extending wall portions being spaced apart to provide an elongated opening therebetween within which a squeegee is positioned.

JOSEPH D. BATES.
